UNITED STATES PATENT OFFICE.

HARRY ALBERT GRIFFITHS, OF EDGBASTON, BIRMINGHAM, ENGLAND.

WORK-FEEDING MECHANISM.

1,164,503.

Specification of Letters Patent. Patented Dec. 14, 1915.

Application filed March 24, 1915. Serial No. 16,651.

To all whom it may concern:

Be it known that I, HARRY ALBERT GRIFFITHS, subject of the King of Great Britain, residing at 22 Francis road, Edgbaston, in the city of Birmingham, England, have invented certain new and useful Improvements Relating to Work-Feeding Mechanism, of which the following is a specification.

This invention relates to cutting, drawing and like presses for operating on metal and other sheets, and, more especially, to those presses which are employed for cutting out from thin metal sheet the blanks employed in the manufacture of small metal boxes and other articles. Such presses are ordinarily provided with two slides at right angles to each other, to one of which the metal sheet is secured. By means of one of the slides the sheet is moved progressively across the tools, and when one row of blanks has been cut out the other slide advances the sheet toward the tools and brings the next row into position. The first slide then feeds the sheet across the tools in the reverse direction to the first. By such movements across the tools and toward the tools successive rows of blanks are removed from the sheet until as much as possible of the sheet has been utilized.

The present invention has for its object to provide improved means for automatically feeding the sheets across the cutting tools.

The invention comprises the combination with a slide, of a pair of racks, and a pawl and stop in conjunction with each rack, the arrangement being such that while the intermittent movements of the slide are being produced in one direction by the action of one of the pawls on one of the racks, the stop in conjunction with the other rack is operating to bring the slide to rest in the correct position at the end of each of such movements.

Referring to the two accompanying sheets of explanatory drawings:—

Figure 1 is a plan, Fig. 2 an end elevation and Fig. 3 a front elevation of feed mechanism constructed in accordance with this invention. Figs. 4 and 5 are respectively plan and front elevation to a larger scale than Figs. 1 to 3 of one part of the feed mechanism, the complete mechanism comprising mainly two of such parts.

In the construction of feed mechanism as

illustrated, a slide *a* which produces the intermittent movements of the sheet across the cutting tools is mounted upon a suitable guide *b*. The slide which produces the movements of the sheet toward the tools at the end of each complete traverse of the slide *a* is mounted on the latter and is indicated by 2. The cutting tools are shown diagrammatically and indicated by 3. It will be understood that the slide *a* and its associated mechanism are mounted on the frame 4 of the machine in any convenient position relative to the cutting tools. The slide *a* has secured to it a pair of parallel rack bars *c* which are adapted to be engaged by oppositely disposed pawls *d*. The pawls engage notches *e* in the bars, which notches are shaped as shown and arranged at equal distances. All the notches of one bar face in the opposite direction to those of the other bar. The pitch or distance between the centers of the notches corresponds to the pitch of the blanks to be cut from the sheet, or the distance the slide is moved at each operation. One pawl produces the intermittent movements of the slide in one direction and the other pawl the corresponding movements in the opposite direction. Each pawl is mounted upon an adjustable block *f* secured to a reciprocatory bar *g* carried in guides or brackets *h* on the framing of the machine, and the two bars are reciprocated in opposite directions. As shown in the drawings the bars *c* and *g* and the pawls are mounted on opposite sides of the slide. Adjacent to each rack bar is mounted a bell-crank lever *i* which is pivoted on a bracket *j* attached to the machine frame. Upon the lever *i* is carried a stop *k* capable not only of a rocking movement with the lever but also of a sliding movement relative to the lever. The stop is situated immediately above the rack bar so that it can engage the teeth in the said bar. Its movement relative to the bell-crank lever is regulated by a blade or other spring *i'* attached to the lever and bearing against one end or other convenient part of the stop. In conjunction with the lower end of each stop is arranged a lever *l* and buffer spring *l'* for the purpose hereinafter described. The said lever and spring are carried on a bracket *m*. Motion of the stop *k* relative to the lever *i* is produced by an adjustable sliding cam or notched bar *p* carried on the pawl block *f*, the bar engaging the stop

through a lateral projection or shoulder *g* on the stop.

In operation the approximate adjustment is effected by the pawl acting on the one notched rack bar *c*, and the final adjustment by the stop engaging the other bar. It will be understood, therefore, that to control the movements of the slide in one direction the pawl of the set of mechanism on one side 16 of the slide and the stop of the set of mechanism on the other side of the slide are employed. The other stop and pawl are out of action, and are brought into use to produce the opposite movements of the slide 20 when the first mentioned pawl and stop are out of action. In Fig. 3 the pawl and stop mechanism on the far side of the slide only is shown and the portion of the guide and the rack bar at the front of the slide are 25 shown as broken away for clearness of illustration. The pawl which operates when the particular stop illustrated is in use is shown in dotted lines as is also the notch which it engages. The operative pawl and the notch it engages are likewise shown in dotted lines 30 in Fig. 5. It will be understood that the dotted pawls and notches belong to the mechanism on the near side of the slide. In Fig. 2 the stop mechanism on both sides of the slide is omitted to avoid confusion.

The major portion of each movement of the slide is produced by the pawl which engages one of the rack bars and is advanced to the required extent by the reciprocating 35 bar on which the pawl is mounted. When the movements are performed rapidly considerable difficulty is experienced owing to the momentum of the slide and the parts associated therewith, and in consequence when 40 rapid operation is required it is impossible to accurately move the slide from one position to the next by means of the pawl only. Usually the pawl is set to move through a distance slightly less than the movement required in the slide, overrunning of the slide 45 being relied upon to make up the deficiency and carry the slide to the proper position. During the movement of the pawl *d* while in engagement with its rack bar *c* the stop *k* adjacent to the other bar *c* slides vertically 50 into engagement with a notch *e* under the action of its spring *i'*. After the pawl has finished its movement the slide *a* is arrested by the engagement of the stop *k* with the 55 one end of the notch *e* which it engages in the other bar *c*. The momentum is absorbed and shock avoided by the rocking of the stop *k* with its lever *i* about the pivot of the latter, such movement being transmitted by 60 the stop to the buffer lever *l* and the spring *l'*. Due to the compression of the buffer the slide *a* is brought to rest gently. The strength of the spring is adjusted so that it 65 brings the slide to rest exactly in the right position. While the pawl *d* and its recip-

rocating bar *g* is returning the other reciprocating bar *g* adjacent to the stop *k* is moving in the opposite direction, and during such movement the cam bar *p* which is secured to and moves with the said bar *g* lifts the stop out of engagement with the rack bar *c*. The bar *g* then continues its movement idly. Meanwhile the bar carrying the operative pawl is approaching its initial position, and when this is reached the above 75 described cycle of operations is repeated. By arranging for approximate movements to be produced by the pawl and the fine adjustments to the proper positions by the stop higher speed of operation is obtainable than 80 with feeding mechanism heretofore employed. To prevent any possibility of recoil of the slide by the spring *l'*, a bar *5* is fixed longitudinally on the guide *b* and arranged alongside the slide *a*. A vulcanized fiber or 85 like bearing surface *6* is provided on the side of the slide adjacent to the bar and the latter is pressed against such surface by a pressure piece *7* carried by the slide and controlled by springs *8*. The friction between the slide and the bar *5* acts as a brake and effectively prevents recoil of the slide 90 after it has been brought to rest by the spring *l'* as above described.

The reciprocation of the bars carrying 95 the pawls is effected by a pair of levers *r* mounted on parallel shafts *t* which are connected by toothed wheels *u*, one of the shafts being rocked from any convenient part of the press mechanism, so that each cutting 100 stroke of the tools is followed by an operation of the slide. For putting the pawls into and out of action alternately a pair of bars *v* are mounted parallel with the slide and provided with lever-like projections *w* for 105 engaging the pawls. The two bars are connected by levers *x* and a link *y* at one end and arranged in conjunction with any convenient throw-over mechanism which is actuated when the slide reaches the ends of 110 its movements. At the completion of the intermittent movements of the slide in one direction the bars *v* are rocked to put the operative pawl out of action and the inoperative pawl into action. The slide then 115 traverses intermittently in the opposite direction, and when it reaches the end of this series of movements the action of the pawls is reversed.

The invention is not limited to the constructional or mechanical details herein described, as these may be varied to meet different requirements. Where adjustability is required in the various parts of the mechanism any convenient provision is made as 120 shown.

Having thus described my invention what I claim as new and desire to secure by Letters Patent is:—

1. In cutting, drawing and like presses 125

for operating on metal and other sheets, means for feeding the sheets comprising, a slide, a pair of oppositely notched racks attached to the slide, a reciprocatory bar and 5 a pawl carried by such bar in conjunction with each rack, also a sliding stop in conjunction with each rack, a lever carrying the stop, a spring buffer abutting against the stop, and means attached to the reciproca- 10 tory bar whereby the stop is intermittently withdrawn from the rack, substantially as described.

2. In cutting, drawing and like presses for operating on metal and other sheets, means 15 for feeding the sheets comprising, a slide, a pair of oppositely notched racks attached to the slide, a reciprocatory bar mounted parallel with each rack, a pawl and a stop actuating device on each bar, means whereby op- 20 posite reciprocatory movements are imparted to the bars, a sliding stop in conjunction with each rack, a lever carrying the stop, a buffer lever abutting at one end against the stop, a spring acting on the other end of the buffer lever, and a spring 25 acting on the stop, substantially as described.

3. In cutting, drawing and like presses for operating on metal and other sheets, means

for feeding the sheets comprising, a slide, a pair of oppositely notched racks attached to 30 the slide, a reciprocatory bar mounted parallel with each rack, a block attached to each bar, a pawl and a notched stop actuating bar carried by the said block, interconnected 35 shafts and levers imparting opposite reciprocatory movements to the bars, a sliding stop arranged in conjunction with each rack and adapted to coöperate with the stop actuating bar, a lever carrying the stop, a buffer lever abutting at one end against the stop, a 40 spring acting on the other end of the buffer lever, a spring acting on the stop, levers and interconnected bars whereby one of the pawls is brought into action and the other put out of action at the end of each 45 complete traverse of the slide, and a brake bar in conjunction with the slide, substantially as described.

In testimony whereof I have signed my name to this specification in the presence of 50 two subscribing witnesses.

HARRY ALBERT GRIFFITHS.
